CLAIM

The ornamental design for an emergency vehicle light assembly, as shown and described.

DESCRIPTION

FIG. 1 is a front perspective view of an emergency vehicle light assembly showing our new design;

FIG. 2 is a rear perspective view thereof;

FIG. 3 is a front elevation view thereof;

FIG. 4 is a right side elevation view thereof;

FIG. 5 is a rear side elevation view thereof;

FIG. 6 is a left side elevation view thereof;

FIG. 7 is a top elevation view thereof; and,

FIG. 8 is a bottom elevation view thereof.

The broken lines shown in FIGS. 1 through 8 illustrate portions of the emergency vehicle light assembly which form no part of the claimed design.

1 Claim, 6 Drawing Sheets
